UNITED STATES PATENT OFFICE.

**BURTON D. MYERS, OF WALLINGFORD, CONNECTICUT, ASSIGNOR TO SIMEON L. AND
GEORGE H. ROGERS CO., OF WALLINGFORD, CONNECTICUT, A CORPORATION OF
MAINE.**

DESIGN FOR A SPOON, FORK, OR SIMILAR ARTICLE.

48,283.

Specification for Design. Patented Dec. 14, 1915.

Application filed July 29, 1915. Serial No. 42,668. Term of patent 7 years.

To all whom it may concern:

Be it known that I, BURTON D. MYERS, a citizen of the United States, residing at Wallingford, in the county of New Haven and State of Connecticut, have invented a new, original, and ornamental Design for Spoons, Forks, or Similar Articles, reference being had to the accompanying drawing, forming part thereof.

The figure is a front view of a spoon, fork or similar article, showing my new design.

I claim:

The ornamental design for a spoon, fork, or similar article, as shown.

BURTON D. MYERS.

Witnesses:

MARGARET HAYDEN,
JOHN F. MOONEY.
